(57) **CLAIM**

The ornamental design for a boat for substrate processing apparatus, as shown and described.

DESCRIPTION

FIG. 1 is a front, top and right side perspective view of a boat for substrate processing apparatus showing my new design; FIG. 2 is a rear, top, and left side perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is a cross-sectional view taken along line 9-9 in FIG. 3 thereof; and, FIG. 10 is a cross-sectional view taken along line 10-10 in FIG. 3 thereof.

1 Claim, 9 Drawing Sheets
